UNITED STATES PATENT OFFICE

GEORGE DEYO, OF ELIZABETH, NEW JERSEY

MASSAGING DEVICE

Application filed July 11, 1930. Serial No. 467,185.

The invention relates to a machine for effectively massaging feet.

For the most beneficial results, feet should be massaged with certain sliding and rotary movements, which heretofore, have required the manual services of an expert. Inasmuch as many patients require frequent foot massages, the constant necessity for expert manual services is inconvenient and expensive.

It is an object of this invention to provide a machine by means of which the hand movements of an expert may be simulated in massaging feet.

A further object is the provision of a foot massaging machine having an automatic control which enables the machine to be used only when the patient is in a sitting position, or lying position or any position other than standing.

A further object is to provide means for adjusting the foot massaging machine to accommodate feet of different sizes, and for regulating the massaging pressure.

These and other objects are attained by the novel construction, combination and arrangement of parts hereinafter described and shown in the accompanying drawings, constituting a material part of this disclosure and in which:

Figure 1 represents a plan view of the massaging machine.

Figure 2 represents a side view of the machine, partly in section, taken on line 2—2 of Figure 1.

Figure 3 represents a plan view of the machine with the covers removed.

Figure 4 represents a sectional view taken on line 4—4 of Figure 3.

Figure 5 represents a sectional view taken on line 5—5 of Figure 3.

Figure 6 represents a sectional view taken on line 6—6 of Figure 3.

Referring to the drawings, the machine includes a casing 7, and a plurality of tapered rollers 8 upon which are placed the feet to be massaged.

Centrally located on the upper surface of casing 7 is a track 9, for guiding a sleeve 10, having a slot 11, through which projects 50 a lock screw 13, adapted to enter threaded re-

cesses 12 in the track 9 to maintain the sleeve 10 in adjusted positions thereon.

Integral with the sleeve 10 are rests 14 for the heels of the feet, and the feet are maintained in engagement with the rollers 8 by 55 elastic bands 15 and 16 connected to the heel rest 14 and to the upper surface of the casing 7.

The rollers 8 are rotatably mounted in a plurality of blocks 17 slidably positioned in a central frame 17'. Mounted on a frame part of 9 is an electric motor 18 having a shaft provided with a worm 19 in mesh with a worm wheel 20 fixed to a shaft carrying a gear 21, in mesh with a gear 22 fixed to shaft 60 23, having rotatably mounted thereon by means of a sleeve a gear 24 with an integral clutch member 25 engageable with a similar clutch member 26 slidably mounted on shaft 65 23.

Clutch member 26 is connected to and moves with a clutch member 27, the latter being engageable with a clutch member 28 integral with a gear 29 fixed to a sleeve 29' 70 rotatable on shaft 23.

Gear 24 meshes with a gear 30 fixed to an auxiliary shaft 31, having also fixed thereto a gear 32 in mesh with idler gear 27', the latter also meshing with gear 29.

Fixed to sleeve 29' is a bevel pinion 33 75 meshing with bevel gear 34 fixed to shaft 35. As will be seen, when clutch members 25 and 26 are in engagement, the bevel pinion 33 will rotate in the opposite direction to shaft 23, and when clutch members 27 and 28 are engaged the bevel pinion will rotate in the direction of shaft 23.

The clutch members 26 and 27 are slidably connected to shaft 23 by means of a pin and slot, and shifted by a forked arm fixed to a shift rod 37, having at one end spaced collars 38 and 39, between which is positioned an arm 40 rotatably mounted on shaft 41 and integral with a plate 42, having a projection 43 in the path of lugs 44 and 45 on the rear of bevel gear 34.

As shown in Figure 6, the projection 43 has been engaged by lug 44 to shift clutch members 27 and 28 into engagement. The bevel gear 34 will now rotate in the opposite 100

direction until lug 45 engages projection 43 to shift clutch members 25 and 26 into engagement.

The plate 42 is provided with a wedge shaped projection 46 in contact with the inclined surfaces of the arm 47 of a lever pivoted at 48, the other arm 49 of the lever being constantly urged in one direction by a compression spring 50 mounted in a recess in the frame 9. By means of this structure, the arm 47 constantly engages the wedge member 46, to maintain the arm 40 in either of two positions.

Fixed to shaft 35 are a plurality of angularly spaced cams 51 engageable with levers 52 and 57, disposed in slots 53 in the blocks 17. It will be noted that the slots 53 are of varying lengths, the lengths of the slots decreasing towards the center of the machine so that the center roller will be raised a greater distance than the end rollers.

In each block 17 is a recess in which is positioned a tension spring 54, having one end suspended on pin 54' under frame 17', and its opposite end resting on a pin 55 secured to a roller, said pin 55 projecting into a recess 56 of the adjacent block 17. (See Figure 2.)

As a block 17 and its associated roller 8 are raised, the projection 55 in recess 56 engages the adjacent block to resist further upward movement of projection 55, resulting in a rotation of the roller 8.

By means of this arrangement, not only is the roller caused to exert an upward pressure against the foot, but a rotary movement is also provided, thus simulating the usual manual massaging movements of an expert.

The last pair of levers 57, at each end of the machine are pivoted to levers 58, rotatably mounted on shaft 41. A notched link 60 is connected to each pair of levers 58 (see Figure 5), and by means of the notches 61 in the link, the latter may engage the casing wall in two positions, so that the levers 58 may be moved to two positions, to vary the leverage of the levers 57.

By means of this arrangement, the extreme pairs of levers 57 at each end of the machine may be adjusted so that they are ineffective in the treatment of short feet. The link 60 is maintained in engagement with the wall of the casing by the pressure of a flat spring 62 attached to the rear end of lever 57.

Electrical current is introduced to the motor through terminals 63 and 64 in casing 7, (see Figure 3), the terminal 63 being directly connected to the motor, from which a conductor 65 leads to a variable resistance coil 66, engaged by a slidable spring contact member 67, the latter being connected to a rod 68, slidable in a tube 69, and engaging the wall thereof to make good electrical contact.

From the tube 69, the conductor is carried to a cam member 70 to which is attached

spring contact 71 adapted to engage an adjustable contact 72 directly connected by a wire 73 to terminal 64. Normally, when the machine is not in use, the spring contact 71 will not be in engagement with adjustable contact 72, however, when the supporting leg 74 is moved to an upright position, it engages the cam 70 and forces spring 71 and contact 72 into engagement to complete the circuit through to the motor. 75

Supporting leg 74 is tubular and telescopes a rod 74' held in adjustable positions therein by detent means (not shown). Leg 74 is pivoted at 75 to the central frame 17', and when the machine is not in use, the leg is rotated 80 in a clockwise direction, (see Figure 2) to an out-of-the-way position. The leg 74 is maintained in an upright position by a bowed latch 76, attached by means of a hinge to the underside of the cover of the machine, the spring 77 urging it downwardly against the leg 74. 85

The levers 52 are pivoted on a block 78, the latter being fixed by pins 59 to shaft 41. Also, non-rotatably mounted on shaft 41 is a collar 79 slidable on the shaft by means of a pin 80 and a slot 81 in the shaft. The collar 79 is provided with an arm 82, engaging an angularly disposed cam 83 projecting laterally from plate 42. 90

The end of shaft 41 is threaded at 84, and is engaged by an internally threaded tube 85 which constantly abuts the collar 79 as the result of the pressure exerted on the collar 79 by a compression spring 87 encircling shaft 100 41 between the collar 79 and a shoulder 88 on shaft 41. The tube 85 may be rotated by a knurled hand grip 86 positioned outside of casing 7. 95

By means of the above described structure 105 the intensity of the massaging action of the rollers may be regulated by regulating the leverage of levers 52. If it is desired to moderate the action of the rollers, shaft 41 is rotated clockwise slightly to move the block 110 78 in the same direction to shift the levers 52 away from the slots in the blocks 17.

The rotation of shaft 41 is accomplished by rotating tube 85 to press collar 79 inwardly, the arm 82 engages cam 83 to rotate plate 115 42. However, rotation of plate 42 is soon limited by the engagement of arm 40 with either collar 88 or 89. Since further rotation of plate 42 has been arrested, the camming action between arm 82 and cam 83, 120 causes a rotative pressure on arm 82 to cause collar 79 to rotate shaft 41, and incidentally shift the fulcrums of levers 52.

In operation, when it is desired to use the machine, the leg 74 is moved to an upright position to close the circuit through the electric motor, and to support the machine in the proper position. The feet are then placed on the rollers 8 and held there by the elastic straps 15 and 16, the patient being in 130

a sitting position, due to the inclination of the machine resulting from the upright position of leg 74.

The speed of the motor may be regulated by the variable resistance 66, and the rollers 8 first rise and fall progressively from the front of the machine to the rear. As the extreme rear roller is completing its movements, the rotation of shaft 35 is reversed, as explained above, and the rollers now rise and fall progressively from the rear to the front.

This alternation of movements is continued throughout the massaging operation, each roller also having a rotary movement as it rises, thus simulating the circular movements of the hand of an expert massager.

From the above description, it will be seen that I have provided a machine for effectively massaging feet, without necessitating the services of an expert.

The foot massaging machine is so constructed to fit any size foot, and may be used either for one foot or both feet; and it is intended for use by the layman and the professional man. The machine is designed to ease the sufferings due from weak feet, and to give relief to tired and aching feet.

This purpose is accomplished by the progressive movement of the rollers, which provide a knuckle or stimulating massage stroke upon the plantar muscles of the foot by the downward stroke of the roller from the toe to the heel, the rollers fitting into the arch of the foot and increasing the pressure up to the highest point in the arch, and hence decreasing in pressure as the rollers rise near the heel.

A palliative or soothing stroke is accomplished by the reversed action of the rollers, the rollers on their way back from the heel to the toe not rising in height as much as when on their way from the toe to the heel.

The movement of the rollers breaks up adhesions, stiffness in the plantar muscles, quickens the circulation, replaces stagnated blood or slowed up circulation with pure oxygenated blood, and helps greatly in building up the tonicity of the muscles by creating a source of better nourishment to the parts, which in turn results in muscle strength.

Due to the force of the gravitation, blood in the body, when it has of necessity been made to work in a position other than lying, is slowed up in the pedal extremities. A stimulating massage immediately followed with a palliative or soothing massage stroke, such as is accomplished in the massage machine herein described, relieves this heaviness from the body and offers great relief to the tired body.

The foot massage machine may be adjusted while in motion to provide any desired massage pressure by manipulating the regulating screw 85 having the knurled knob 86. This regulation of the massaging pressure is im-

portant when massaging feet with varying degrees of arches. A person with a flat foot may not need, at first, a heavy massage stroke. Similarly a person with a high arch, in order to feel the effects of the massage stroke, will of necessity need to increase the massage pressure, and this may be readily done by manipulating the regulating screw.

Another feature of the machine is that it is foolproof, in that it may not be operated while in a horizontal position. It will be readily seen that the electrical circuit through the motor will be closed only when the leg 74 is in an upright position, and the machine is in an inclined one. Consequently, a person in a standing position, will be unable to use the machine, as he cannot very well stand on it while it is inclined and maintain his equilibrium.

Therefore, in order to receive the benefit of the machine, he must be of necessity, in a position other than standing such as sitting or lying down in a relaxed position.

The purpose of the reversing of the motion of the machine is to stimulate and then to soothe. The forward stroke from toe to heel of the rollers offers stimulation by increased pressure from the rollers, at the same time breaking up the stiffness.

The return stroke is a soothing stroke, and the forward motion may be favorably compared with the palm surface of the hand stroking the plantar surface of the foot, during a manual massage by an expert. Also, the partial rotation of each roller causes some friction which is also a massage benefit.

The foregoing disclosure is to be regarded as descriptive and illustrative only, and not as restrictive or limitative of the invention, of which obviously an embodiment may be constructed including modifications without departing from the general scope herein indicated and denoted in the appended claims.

Having thus described my invention, what I claim as new and desire to secure by Letters Patent, is:

1. A foot massaging machine, comprising a frame, a plurality of blocks slidable vertically on the frame, a tapered roller carried by each block, said blocks having slots of varying lengths, levers positioned in the slot, and means for progressively rotating the levers to raise the blocks.

2. A foot massaging machine, comprising a plurality of blocks slidable vertically, a roller carried by each block, said blocks having slots of varying lengths, levers positioned in the slots, a shaft, a plurality of angularly spaced cams fixed to the shaft, said cams engaging the levers, and means for rotating the shaft.

3. A foot massaging machine, comprising a plurality of blocks, a roller carried by each block, levers engaging said blocks, a shaft, a plurality of cams fixed to the shaft and en-

gageable with the levers, means for rotating the shaft, and means for shifting the fulcrums of the levers.

4. A foot massaging machine, comprising a plurality of blocks, a roller carried by each block, levers engaging the blocks to raise and lower the latter, a shaft, a plurality of cams fixed to the shaft and engageable with the levers, means for rotating the shaft, and means for reversing the rotation of the shaft at predetermined intervals.

5. In a foot massaging machine, a plurality of levers, a shaft, a plurality of cams fixed to the shaft and engaging the levers, means for rotating the shaft, and means for periodically reversing the direction of rotation of the shaft.

6. In a foot massaging machine, a slidable block having a recess, a roller rotatably mounted in the block, a tension spring positioned in the recess and having one end connected to the roller and its other end attached to a fixed support, means for raising the block, and means engaged by an end of the spring when the block is raised to cause a partial rotation of the roller.

7. In a massaging machine, a frame, an electrical circuit having a resilient switch therein, a support pivoted to the frame, and means associated with the support and switch to close said circuit when the support is moved to an upright position.

8. In a foot massaging machine, a plurality of rollers, a plurality of levers, means connecting the levers and rollers, and means to raise the levers progressively.

9. In a foot massaging machine, a plurality of levers, a shaft, a plurality of cams fixed to the shaft and engaging said levers and means for rotating the shaft.

10. In a foot massaging machine, an electrical circuit having a switch normally open when the machine is in a horizontal position, a support for raising the machine to an inclined position, and means associated with said support to close the switch when the machine is raised to an inclined position.

11. In a foot massaging machine, a plurality of levers, a block to which said levers are pivoted, a shaft on which the block is fixed, and means for angularly adjusting the position of the shaft whereby the position of the fulcrums of the levers may be changed.

12. In a foot massaging machine, a plurality of levers, a shaft having angularly spaced cams engageable with the levers, means for rotating the shaft, and a plurality of rollers associated with the levers, said rollers being progressively raised as the shaft rotates.

13. In a massaging machine, an electrical circuit, a pivoted support, and means associated with the support to close the electric circuit when the support is in an upright po-

sition so that the machine may be used only in an inclined position.

This specification signed this 11th day of June, 1930.
